UNITED STATES PATENT OFFICE.

HERMENEGILDE CARRIER, OF AMESBURY, MASSACHUSETTS, ASSIGNOR TO G. W. J. MURPHY COMPANY, OF AMESBURY, MASSACHUSETTS, A CORPORATION OF MASSACHUSETTS.

STOP HINGE.

Application filed May 28, 1925. Serial No. 33,445.

This invention relates to hinges and the object is to provide a neat, durable and inexpensive hinge provided with suitable means for limiting the opening movement thereof.

As an example of my invention I have herein shown a form of hinge which may be utilized in connection with other hinges of conventional type as a door stop to limit the opening of a door such, for instance, as the door of an automobile. My invention will be readily understood by reference to the following description of that illustrative embodiment shown in the accompanying drawings, wherein:

Fig. 1 is a horizontal section through a portion of the hinge pillar of a vehicle body and the adjacent portion of the door, the door being in open position;

Fig. 2 is a similar view with the door closed;

Fig. 3 is a plan view of the stop partially straightened out;

Fig. 4 is a side elevation of the same; and

Figs. 5 and 6 are views similar to Fig. 4 showing the central leaves in successive positions which they occupy as the door moves toward its position of maximum opening.

My invention is herein disclosed as embodied in a device to limit the opening movement of a door so that it will not swing open too far. For example, it will not swing through an angle of 180° and bang against the body of the vehicle on which it is mounted and mar the same. The construction takes the place of the strap or loop commonly used for this purpose on vehicle doors and is arranged to permit the door to open freely and to stand open, if desired.

Referring particularly to Figs. 1 and 2 of the drawings, the stop, which may be applied to a door hinged in the customary manner, may take the form of a series of hinge leaves 7, 9, 11 and 13, the leaves 9 and 11 being adapted to extend between points of the hinge pillar 15 and the hinge stile 17 which separate from one another in the opening of the door and to form a foldable connection adapted to lie between the pillar and stile and be housed in suitable mortises therein when the door is shut, as shown in Fig. 2, and to open out and extend substantially diagonally across the angle therebetween when the door is swung open, as shown in Fig. 1.

It will be obvious that as the leaves 9 and 11 come into alignment or into such proximity to alignment as may be permitted by suitable stop means provided thereon, they will serve as a connection across this angle between the door and the hinge pillar and prevent further opening movement of the door about its hinges 19. The leaves 7 and 13 provide convenient means for securing the ends of the leaves 9 and 11 to the door and to the hinge pillar, they being preferably attached by screws to the inner faces of the same, as shown in Figs. 1 and 2 of the drawings.

The toggle formed by the links 9 and 11 should obviously be prevented from being thrown over past dead center in order that it may always close between the hinge pillar and hinge stile in the manner indicated in Fig. 2. For this purpose suitable stop means may be provided. The throwing open of a heavy door, perhaps with considerable violence, would cause a heavy shock on such stop means. My invention aims to provide a construction minimizing such shock while permitting the door to be opened freely and without resistance and to stand in the open position without objectionable rebound. I further aim to provide a durable construction which will withstand the shocks of use and yet which may be constructed very cheaply and will be neat and compact.

The leaves 7, 9, 11 and 13 may conveniently be formed as shown of flat strips of metal rolled to form hinge knuckles. Such a construction is obviously simple and cheap and the construction to be described permits the use of such a simple form of hinge connection which might otherwise be considered insufficiently staunch.

To check movement of the leaves 9 and 11 as they approach dead center position, which in the embodiment of the invention shown corresponds closely to the maximum opening of the door, I provide suitable resilient means which will oppose the straightening out of the toggle, such resilient means being arranged to come into action during the latter part of the opening movement of the hinge only shortly before it reaches its desired maximum opening so that the door may open freely and may, if desired, stand open in the position of Fig. 1 without any tendency to reclose. I further provide a positive

stop preventing a relative movement of the leaves beyond the desired maximum, the shock which would otherwise fall upon the stop being minimized by the action of the resilient means referred to. To provide for these functions in a most convenient manner I may rivet to leaf 11 a flat spring 21 having its end extending past the hinge joint between the leaves 9 and 11 and presented to the back of the leaf 9 so as to come in contact therewith and bear thereagainst shortly before the leaves assume the position shown in Fig. 1 and to yield resiliently on further movement of the leaves toward alignment. Thus in Fig. 4 I have illustrated the spring as just making contact with the back of the leaf 9 and in Fig. 5 the leaves 9 and 11 have been somewhat further straightened and the spring 11 has been tensioned as indicated.

It will be apparent that when the door is thrown open the leaves 9 and 11 will first open freely without any resistance until they come to the position of Fig. 4. The spring 21 then coming into contact with the leaf is deflected by the further straightening movement, as shown in Fig. 5, cushioning this movement. To definitely limit the movement a suitable positive stop may be provided which is conveniently formed by striking up the projection 23 from leaf 9 on which projection the end of the spring 21 will seat in the manner shown in Fig. 6 preferably at a point slightly in advance of the dead center position of the pivots. I have referred to this stop as positive although obviously there may be a slight yielding of the spring but it is substantially a definite stop as compared with the action of the spring between the positions shown in Figs. 4 and 5. When the parts have reached the positions of Figs. 1 and 6, obviously the opening movement of the door is definitely stopped. In the latter part of this straightening action, that is, the period between the positions of Figs. 4 and 5, the movement has been cushioned and no sharp shock has been thrown upon the pintles and knuckles and while the positive stop is provided in a very convenient manner, it does not operate with a hammer blow as might be the case with ordinary shoulders on the hinge knuckles operating in the manner of a so-called rule joint. Furthermore, in the preferred construction shown the hinge knuckles may, as already described, be formed as simple rolled knuckles most expeditiously and cheaply.

When the parts have reached the position shown in Fig. 6, the reaction of the spring

may tend to return the leaves toward the position of Fig. 5 but there is no sharp rebounding movement which would tend to reclose the door as in the case of a hinge which is operated against the spring throughout its opening movement. The leaves being definitely stopped before they reach dead center, there is no danger of the toggle breaking in the reverse direction so that instead of the links returning to their inconspicuous housed position between the hinge pillar and the hinge stile, as shown in Fig. 2, they would project into the interior of the vehicle when the door is closed. Furthermore, such reverse breaking of the toggle, if possible, might permit the door to rebound and the tendency of the links folding in the other direction would be to shut it prematurely.

I have described in detail the particular embodiment of my invention shown by way of example in the accompanying drawings. Obviously the invention is capable of other applications and of mechanical embodiments considerably different from that shown.

What I claim as new and desire to secure by Letters Patent I shall express in the following claims:

1. A stop hinge comprising a pair of leaves pivoted together and a flat spring secured to one leaf having an end extending over the pivot and presented to engage the other leaf only shortly before the hinge reaches its desired maximum opening, said other leaf having a projection on which the spring seats when such maximum opening is attained.

2. A stop hinge comprising a pair of leaves pivoted together, a stop for positively preventing relative opening movement of the leaves beyond a desired maximum and spring means effective only during the latter portion of the opening movement of the hinge for cushioning such movement and minimizing the blow on the stop.

3. A door stop comprising a pair of hinged leaves provided with means for connecting them pivotally to the hinge pillar and hinge stile, said leaves adapted to fold between pillar and stile when the door is closed and extend substantially diagonally therebetween when it is open, means positively limiting the opening movement of the leaves and cooperating resilient means opposing their hinging during the lattermost part only of their opening movement.

In testimony whereof, I have signed my name to this specification.

HERMENEGILDE CARRIER.
